ELECTROLYSIS OF ALKALINE METAL CHLORIDES AND APPARATUS THEREFOR

Erich Müller, Dresden, Germany, assignor, by
mesne assignments, to Th. Goldschmidt Corporation,
New York, N. Y., a corporation of Delaware

Application June 24, 1937, Serial No. 150,021
In Germany April 13, 1937

2 Claims. (Cl. 204—99)

This invention relates to electrolysis of alkaline metal chlorides and apparatus therefor; and it includes a process which comprises passing an alkaline metal chloride solution through an electrolytic cell while electrolyzing the same, passing a stream of mercury through said electrolytic cell; the mercury serving as cathode and being converted to alkaline metal amalgam during the process; passing the resulting amalgam through an amalgam-decomposing cell having an inclined bottom, of catalytic material, formed in spaced parallel tracks, in contact with an amalgam-decomposing solution; the said mercury being passed into said electrolytic cell intermittently in pulsations of sufficient magnitude to produce a pulsating flow through said cell and into the amalgam decomposing cell where it is broken up into droplets which roll in said tracks along the inclined bottom, thereby producing a maximum surface exposure; collecting the mercury from the decomposing cell and returning it to the electrolytic cell. My invention further includes an apparatus for conducting said process, said apparatus comprising an electrolytic cell and an amalgam-decomposing cell, means for introducing mercury intermittently in a pulsating flow into said electrolytic cell, means for passing an alkaline metal chloride solution through said cell, means for passing the resulting amalgamated mercury from said electrolytic cell into said decomposing cell without substantial disturbance of said pulsating flow, means including a sloping cell bottom formed in spaced parallel tracks for passing the partially amalgamated mercury through said decomposing cell in the form of droplets and in contact with a decomposing liquor, and means for returning the resulting mercury to the electrolytic cell; all as more fully hereinafter set forth and as claimed.

Many different methods have been proposed in the prior art for electrolyzing alkali metal chloride solutions. In several of these methods use is made of a flowing mercury cathode. And a number of different electrolytic cell designs have been proposed for this process. The mercury which acts as cathode usually flows over the floor of the electrolytic cell while a sodium chloride solution is passed over this mercury. This solution is electrolyzed as it passes through the cell between the mercury cathode and the anodes, usually of carbon. Chlorine is evolved at the anodes and is passed out of the cell and recovered. The mercury in passing through the cell is partially converted to sodium amalgam and this is

then decomposed by means of water or an aqueous solution into mercury and caustic soda in a separate decomposing cell. The hydrogen formed during the decomposition is collected separately. A catalyst, such as graphite, is usually employed in the decomposing cell to assist in the decomposition of the amalgam. The mercury which is recovered from the latter cell is then recycled to the electrolytic cell to be used in a repetition of the process. In the commercial operation of this process various difficulties have arisen.

When the conventional carbon anodes are employed in the electrolytic cell it has been found that these anodes tend to disintegrate slowly. This causes the production of fine carbon particles which, of course, tend to float on the surface of the mercury or of the amalgam. These carbon impurities, as well as the iron amalgam impurities which are usually present, due to a slight reaction between the mercury and the iron of the containing vessels, tend to act catalytically causing the decomposition of the amalgam in the electrolytic cell. This leads to the formation of hydrogen gas which, of course, is liable to form explosive mixtures with the chlorine evolved in the electrolytic cell.

The difficulties caused by impurities in the mercury can be mitigated to some extent by the provision of a plurality of transverse weirs across the floor of the electrolytic cell over which the mercury is forced to pass seriatim, the floor of the cell being stepped downwardly from the entrance to the exit. The impurities are thus forced to pass over the weirs and a return is rendered impossible.

The same impurities cause difficulties in the amalgam-decomposing cell. In the conventional decomposing cell the alkali metal amalgam is slowly passed across the floor of the cell in countercurrent to a flow of water, the floor of the cell being usually constructed of catalytic material such as graphite. Grids of catalytic material are also provided which project above the surface of the mercury. It has been found that the passages between the grids become obstructed by the impurities in the amalgam. Furthermore in this type of decomposing cell the floor of the cell is completely covered with amalgam which therefore also covers the surface of any catalytic material of which the floor is constructed. This surface is thereby rendered inactive. Even when a grid of catalytic material is employed, the decomposition of the amalgam in the cell is slow. One cause for this is that the more dilute amalgam

gam is more dense than the more concentrated amalgam. The latter therefore tends to float and to become highly viscous on its surface, especially if it contains any substantial quantities of impurities. The fluidity of the surface of the amalgam is considerably less than that of the heavier and more dilute amalgam on the floor of the cell. The amalgam therefore tends to flow along the floor of the cell to the exit without coming in contact with the decomposing liquor and therefore without decomposing. The surface of the amalgam tends to become stagnant and a delayed decomposition as well as a lowered efficiency is an inevitable result.

15 I have found that the enumerated difficulties which arise in the decomposing cell can be eliminated in a surprisingly easy and commercially feasible manner. This is accomplished by slightly tilting the floor of the cell downwardly towards the exit and providing a pulsating flow of the amalgam to the cell. The amalgam then tends to form in droplets which are flattened more or less and which roll across the floor of the cell thus continuously supplying fresh amalgam surfaces to the action of the decomposing liquor and also exposing the floor of the cell, thus rendering active its catalytic surface. The three-phase line-contact of catalyst, amalgam and decomposing liquid, which is required in the decomposition of the amalgam, is increased many fold by this method and is continuously renewed. Decomposition is more complete and is accomplished in a fraction of the time required by the older method. The rate of decomposition is increased still further by the provision of a catalytic grid comprising spaced parallel bars running longitudinally along the floor of the cell, these bars forming spaced tracks for the flow of amalgam droplets. This prevents coalescence of the droplets and provides a uniform flow of droplets across the floor of the cell. Furthermore the total quantity of mercury-amalgam mixture in the decomposing cell is greatly reduced and this reduces the quantity of mercury required in the process as a whole. A pulsating flow of mercury through the electrolytic cell is employed in combination with a similar flow through the decomposing cell. It is usually possible to produce a positive pulsating flow at one point in the cycle, the pulsations carrying over from one cell to the other. If a positive pulsating flow is provided for the electrolytic cell, by means of a pump for example, these pulsations will cause the mercury to flow in pulsations throughout the length of this cell and, if the amalgam leaving this cell is caused to flow into the decomposing cell in a manner preventing disturbance of these pulsations, the flow into the latter cell will also be in the form of pulsations, these pulsations being usually sufficient to produce a flow of droplets across the floor of the decomposing cell in the manner described previously.

65 It is possible, of course, to produce independent and positive pulsations in the flow of the mercury through the decomposing cell. This can be accomplished by vibrating or rocking the decomposing cell, for example. If the decomposing cell is vibrated these vibrations tend to break up the droplets of amalgam and to increase further the surface exposed to the action of the catalyst and decomposing liquor.

70 The pulsating flow in the electrolytic cell has the added advantage of producing a positive propulsion of the impurities towards the cell exit.

These floating impurities are lifted over any weirs provided in this cell by the pulsations and may be collected in a well at the lower end and removed without disturbing the operation of the process. It is also advantageous to provide a similar well at the lower end of the decomposing cell from which the impurities may be removed prior to passing the mercury into the electrolytic cell.

75 It is advantageous but not essential to provide a counter current flow of water, as decomposing liquid, and of amalgam in the decomposing cell. The fresh water then comes into contact with the most dilute amalgam while the most concentrated caustic alkali solution in the cell is contacted with the amalgam as it enters the cell. 10 The stirring action which is produced by the evolution of hydrogen in this cell can be minimized by the use of a low head of decomposing liquor in the cell.

15 My invention can be explained in greater detail by reference to the accompanying drawing which shows an assembly of apparatus elements within the purview of my invention and useful in the conduct of my process. In this showing,

20 Fig. 1 represents a vertical longitudinal section through the electrolytic cell and the amalgam-decomposing cell with related apparatus, while

25 Fig. 2 is a vertical transverse section through the amalgam-decomposing cell, taken along the line 2—2 of Fig. 1.

30 In the drawing like parts are represented by like reference numerals. The electrolytic cell is designated generally by the reference numeral 1, the amalgam-decomposing cell being similarly designated at 2. The bottom of the electrolytic cell is stepped, as shown, forming a series of trays 3^a, 3^b, 3^c and 3^d which are separated by the transverse weirs 4^a, 4^b, 4^c, 4^d and 4^e over which the mercury 5 passes on its way through the cell. The mercury is introduced into the cell from a vessel 6 whose lower end is closed by means of a hollow cylinder 7 which is provided with a slot 8. The cylinder is rotated by means of a shaft 9 and pulley 10 which is driven by means not shown. It will be evident that, at every rotation of the cylinder 7, a charge of mercury is collected in the cylinder which charge flows into the well 11. The resulting pulsating flow of mercury passes 40 under the dam 12, over the weir 4^a upon the tray 3^a, then over the weir 4^b and so on from tray to tray finally passing over weir 4^e through the opening 14 formed below the dam 15 and into the well 13 at the opposite end of the cell. The well 55 13 is provided with a cover 20. The solution of alkali metal chloride enters the cell through the pipe 16 and leaves at 17. The chlorine evolved is removed at 18. The anodes, usually of carbon or graphite, are shown at 19. The mercury, of course, forms the cathode. Electrical connections to the anodes and to the mercury cathode are made as shown in the drawing. The connection to the mercury cathode may be made 60 through the floor of the cell if this is made of metal.

65 The mercury is transformed into alkali metal amalgam in passing through the electrolytic cell and this is collected in the well 13. Various impurities collect on top of this product and may be drawn off through the opening below the cover 20. The amalgam, substantially free from impurities, is drawn off by the tube 21 which connects with the bottom of the well 13. The amal- 75

gam is then passed into the well 22 of the decomposing vessel or cell.

The decomposing cell 2 is provided with a sloping bottom 35 which is advantageously made of catalytic material, such as graphite. A grid 23, usually of the same material, is supported on the bottom of the cell. This grid is made of a series of spaced parallel strips, as shown best in Fig. 2, which serve to divide the mercury flowing along 10 the bottom of the cell into a plurality of parallel streams.

The pulsating feed to the electrolytic cell produces corresponding pulsations through the tube 21 to the decomposing cell. This pulsating feed 15 causes the amalgam to flow over the bottom of the decomposing cell in the form of a series of droplets as indicated in Fig. 1, each impulse producing a drop in each of the parallel tracks formed by the grid 23. The catalytic bottom of 20 the decomposing cell is exposed to the decomposing liquor between the drops of amalgam. And it is evident that, as the drops of amalgam roll along the catalytic floor, they continuously expose fresh surfaces to the action of the decomposing liquor and to the catalytic surfaces, thus 25 promoting a very rapid decomposition of the alkali metal amalgam.

The amalgam is decomposed in passing 30 through the cell forming mercury which passes under the dam 25 and falls into the well 24 at the left hand end of the decomposing cell. Any impurities which collect on the top of the mercury in well 24 can be removed by skimming, for 35 example, through the opening 26 at the top of the well 24, without disturbing the operation of the process. The mercury is drawn off from the bottom of the well 24 and falls into a container 27. The pump 28 draws the mercury from the container 27, and delivers it to the vessel 6 from 40 which point it is again fed to the electrolytic cell, to complete the cycle.

The decomposing cell is supplied with water or 45 other decomposing liquor at 29 and the caustic solution which is formed during decomposition of the amalgam flows out of the cell at 30. The hydrogen generated in the cell is removed at 31.

While, as stated previously, the pulsations produced by the cylinder 7, as the mercury is fed 50 into the electrolytic cell, are generally sufficient to produce a corresponding pulsating flow into the decomposing cell, it is frequently advantageous, especially in the case of large-scale operations, to provide for more positive pulsations in 55 the flow of the mercury along the floor of the decomposing cell. This can be accomplished, for example, by vibrating or rocking the decomposing cell and thus producing a pulsating flow of mercury in the form of droplets across the floor 60 of this cell. A method for accomplishing this result is shown in the drawing. The bottom of the decomposing cell may be supported at one end by one or more cams 32, these cams being driven by means of a shaft 33 and pulley 34. As the end 65 of the cell is raised by the high point of the cams a wave of the partially amalgamated mercury flows over from the well 22 upon the floor of the decomposing cell. This amalgamated mercury is broken up into droplets by means of the grid 23 which droplets then roll over the floor of the cell as indicated in the drawing. Substantially the same result can be accomplished by the use of one of the conventional electrical vibrators which may be attached to the floor of the decomposing cell. The amplitude and the frequency of

the vibrations produced in this manner can be readily controlled in order to produce droplets of the desired size. Any feeding method may be employed which produces a subdivision of the mercury as it flows over the floor of the decomposing cell in such manner that the catalytic surface thereof is exposed to the decomposing liquor. Subdivision of the mercury is advantageously produced both longitudinally as well as transversely of the cell, by means of a grid, for 10 example.

While I have described what I consider to be the best embodiments of my invention, it is obvious that various modifications can be made without departing from the purview thereof. 15 For example, either or both the electrolytic cell and the decomposing cell can be vibrated or rocked to produce the desired pulsating flow of mercury and amalgam. The pulsating flow of amalgam to the decomposing cell can be supplied 20 by means of a slotted piston similar to that shown at 7 in the drawing if desired. My process can be applied to the decomposition of any of the alkaline metal chlorides, including chlorides 25 of the alkali metals and of the alkaline earth metals. The mercury or amalgam can be passed in counter current to or in parallel with the flow of the aqueous liquor in either or both of the cells. As a decomposition liquor, water, a caustic 30 alkali solution or any other aqueous solution can be employed. It is not essential that the floor of the decomposing cell be made of catalytic material since the use of a pulsating flow of mercury 35 through this cell, in accordance with my invention, has advantages even when this floor is of inert material. The impurities which collect in wells 13 and 24 may be removed mechanically if desired either continuously or intermittently. Other modifications which fall within the scope 40 of the following claims will be immediately evident to those skilled in this art.

What I claim is:

1. In the process of electrolyzing alkaline metal chloride solutions wherein such a solution is electrolyzed in a cell employing a flowing mercury cathode and the resulting amalgam is transferred by means of a tube to an amalgam decomposing cell having a floor of catalytic material formed into continuous spaced parallel tracks sloping downwardly from the entrance to the exit, the steps which comprise introducing mercury into the electrolytic cell intermittently in pulsations of sufficient magnitude to produce a pulsating flow through said cell, through said tube and into said amalgam decomposing cell at the upper edge of said sloping floor, the flow of amalgam along the upper edge of said sloping floor dividing into a plurality of streams, the pulsations in said flow being sufficient in magnitude 60 and the slope of said floor being sufficient to cause said streams of amalgam to break into droplets at each pulsation, whereby said droplets roll in said tracks to the exit of the amalgam decomposing cell while being converted into mercury, collecting said mercury at the lower end of said sloping floor and returning it to the electrolytic cell.

2. In an apparatus for the electric decomposition of alkaline metal chloride solutions, an electrolytic cell provided with a flowing mercury cathode for decomposing such solutions in combination with an amalgam decomposing cell having a floor of catalytic material formed in continuous spaced parallel tracks which slope down- 75

wardly from the entrance thereof to the exit, means for introducing mercury into said electrolytic cell intermittently in pulsations of substantial magnitude, means for electrolyzing said mercury and converting it into amalgam in said cell, means for transferring said amalgam without substantial disturbance of said pulsations from said electrolytic cell to the upper end of said sloping floor of the amalgam decomposing cell, 5 said tracks being adapted to divide said amalgam into a plurality of streams along the sloping floor

of said amalgam decomposing cell, the pulsations in said flow being sufficient in magnitude and the slope of said floor being sufficient to subdivide the amalgam into droplets at each pulsation whereby said droplets flow in said tracks across said sloping floor to the exit of said amalgam decomposing cell while being converted into mercury, and means for transferring the resulting mercury to said electrolytic cell. 10

ERICH MÜLLER.
